UNITED STATES PATENT OFFICE.

WILLIAM R. STRICKLAND, OF CLEVELAND, OHIO, ASSIGNOR TO THE PEERLESS MOTOR CAR COMPANY, OF CLEVELAND, OHIO, A CORPORATION OF OHIO.

INTERNAL-COMBUSTION ENGINE.

1,381,516.

Specification of Letters Patent. Patented June 14, 1921.

Application filed September 16, 1918. Serial No. 254,271.

To all whom it may concern:

Be it known that I, WILLIAM R. STRICKLAND, a citizen of the United States, residing at Cleveland, in the county of Cuyahoga and State of Ohio, have invented a certain new and useful Improvement in Internal-Combustion Engines, of which the following is a full, clear, and exact description.

This invention relates to internal combustion engines and has for one of its objects to provide means for preventing oil being carried by the rapid circulation of air due to the rotating parts, to the cylinders of the engine, and for preventing the 10 cranks and ends of the connecting rods dipping into the oil when the vehicle driven by the engine is going up or down hill.

A further object is to provide means for preventing oil being blown upwardly along 20 the wall of the crank-case and into the lower ends of the cylinders by the air currents created by the rotating crank-shaft and parts connected thereto.

The above and other more specific objects 25 which will be brought out in the following description are attained by my invention which includes two prime features which while admirably adapted for conjoint use and coöperating when so used to accomplish the objects above stated, have utility 30 though employed independently. One of these parts or features consists of a pan of novel shape and construction positioned between the crank-shaft and lower part of 35 the crank-case, and the other part resides in a baffle placed along the wall against which the air currents are driven by the air currents sweeping through the lower part of the crank-case, and arranged to divert and 40 reduce the effects of the air currents in so far as they tend to drive the oil along said wall up into the cylinders.

The invention may be further briefly 45 summarized as consisting in certain novel details of construction and combinations and arrangements of parts which will be described in the specification and set forth in the appended claims.

In the accompanying sheet of drawings 50 wherein I have shown the preferred form of my invention, Figure 1 is a transverse sectional view, looking rearwardly, through an engine such as is employed on motor ve-

hicles and equipped with my invention; Fig. 2 is a longitudinal sectional view 55 through the lower part of the crank-case showing the crank-shaft and portions of the connecting rods by dotted lines; Fig. 3 is a view on a reduced scale similar to Fig. 1, showing a modification wherein the baffle 60 is employed independently of the pan; Fig. 4 is a view on a reduced scale, similar to Fig. 1, showing a modification in the shape of the pan; and Fig. 5 is a plan view of a pan detached, showing a further modification. 65

The engine here shown, is of the V-type such as an engine of eight, twelve, or more cylinders, though it is to be understood that my invention in all its aspects has utility 70 also in an engine having vertical bore cylinders. The engine here shown has a crank-case composed of an upper part 10 and a lower part 11, and diagonally disposed cylinders 12. The usual crank-shaft 13 is likewise provided, having crank portions connected to connecting rods 14 whose outer ends will be connected to the pistons in the customary manner.

In accordance with my invention, I provide 80 between the crank-shaft and the parts rotating therewith, and the bottom of the crank-case, a pan or receptacle 15, which in this case is separate from the lower half of the crank-case, in which event it is preferably formed of sheet metal, though it may be cast integral with the lower half of the crank-case. This pan is closed on all four sides, being open at the top only, and it is secured to the two opposite sides of the 85 crank-case by bolts 16, though it is spaced from the sides of the crank-case by spacing members 17 surrounding the bolts, and is preferably spaced also from both ends. The spacing of this pan from the sides of the 90 crank-case is of importance as it is desired that the oil be free to flow downward along the sides of the crank-case into the sump, and the spacing from the front end of the crank-case is of importance as it is desired 95 that the oil be free to flow from the gear housing (not shown) commonly provided at the front of the crank-case, into the front end of the latter, without entering the pan, it being common practice to deliver the excess oil from the oil line of the crank-shaft 100 105

to this gear housing. At this point it may be mentioned that oil may be fed to the bearings by any of the well-known types of force feed systems.

- 5 I prefer to provide only one opening for the escape of oil from this pan to the sump, and this opening I place near the center of the pan on the off side from the direction of rotation, *i. e.* near the upright wall toward 70
- 10 which the air is blown by the rotation of the crank-shaft and the parts connected to it in sweeping through the lower part of the crank-case. Additionally it should be noted that as here shown, the bottom of this pan is 15 inclined downward toward the off side from the direction of rotation. This is not, however, an essential feature, as the bottom might be substantially flat, but in that event the outlet opening would be located as 20 shown. The main idea is to form a pocket protected from the full force of the air currents, allowing the oil to separate from the air currents and drain into the sump. The action might be supplemented by channels 25 pressed into the pan and running lengthwise or diagonally toward the centrally disposed drain opening as shown in Fig. 5.

At the rear end of the pan I provide a transverse baffle 18 which extends downwardly beneath the pan within a short distance from the bottom of the cranks, the purpose of this baffle being to prevent slushing of the oil, and to minimize banking in going up or down hill. A similar baffle 18^a may be 30 provided at the front end for the same purpose.

Additionally I provide along that side wall of the crank-case toward which the air currents are driven by those portions of the 40 crank-shaft and parts associated with it in sweeping through the lower part of the crank-case, a baffle 19. This baffle, which may be formed either of sheet or cast metal, but preferably of the former, is attached to 45 the lower portion of the upper half of the crank-case by bolts 20, and spacers 21 are provided around the bolts to space the baffle from the crank-case wall. This baffle 19 extends well up along the upper half of the 50 crank-case, and its upper portion is preferably bent or inclined inwardly, and if it is inclined inwardly far enough, and is employed on an engine of the V-type as herein illustrated, the upper portion is provided 55 with notches 22 to form clearance spaces for the connecting rods associated with the cylinders on the side of the engine to which the baffle plate is applied.

Additionally this baffle extends downwardly into the lower half of the crank-case a distance which will depend upon whether or not the pan described above, is utilized with it. If employed with the pan, it is only necessary that the lower end of the baffle extend downwardly a short distance beneath 60

the top of the pan between the wall of the crank-case and the adjacent side of the pan as shown in Fig. 1. In that event, the side of the pan forms in effect a continuation of the baffle, but if this baffle is employed without the pan, then it is preferably extended well down toward the bottom of the crank-case, as illustrated in Fig. 3, where the baffle is designated 19^a. 70

Regardless of the distance that the baffle 75 19 is extended down into the lower half of the crank-case, that is to say, whether it is employed with or without the pan, its lower edge is bent or extended outwardly so as to bear against the wall of the crank-case, and 80 is provided at intervals with drain openings 23, so that the oil flowing downwardly behind the baffle can readily pass to the sump. 85

It was previously stated that the bottom of the pan might be flat instead of inclined. 90 This is shown in Fig. 4, wherein the pan is designated 15^c. If the bottom of the pan is flat, as here shown, or substantially flat, I prefer to provide along the bottom of the pan and next to the wall toward which the 95 air currents tend to blow the oil, a depression or gutter 15^d constituting a pocket, so that the oil can run into this gutter and be protected from the full force of the air. At about the center of the gutter a drain opening 15^e is provided.

It was previously stated also, that the bottom of the pan might be provided with additional means for protecting the oil from the full force of the air, and that this might 100 be accomplished by the provision of channels or depressions along which the oil flows to the drain opening. This I have illustrated in Fig. 5, wherein the gutters or channels referred to are designated 15^f, and are shown 105 connected to the drain opening 15^g located as in the other cases. These channels can extend longitudinally of the bottom of the pan, or diagonally, or it may be desirable that both arrangements be utilized such as illustrated in Fig. 5. These channels could be employed whether or not the bottom of the 110 pan is inclined as shown in Fig. 1.

The advantages of the construction above described are as follows: The pan minimizes 115 and virtually prevents oil being picked up by the rotating air currents, this being particularly important with high speed motors which cause the air to be circulated in the crank-case at extremely high velocities. Additionally by reason of the fact that the outlet opening in the bottom of the pan is located about midway between its ends, and because the pan, except for this opening is closed on all sides and at the bottom, in going up or down hill the oil is virtually prevented, though banked at one end by the tilting of the motor, from entering the pan, so that the ends of the connecting rods cannot dip in the oil and throw the oil up into the 120 125 130

cylinders as has been the case with the major portion of the prior engine constructions of which I am aware.

At this point it may be stated that I am aware of the fact that it has heretofore been proposed to break the effects of the air as far as picking up oil is concerned, by the provision of horizontal barriers between the crank-shaft and the base of the crank-case, but in all such instances of which I am aware, these barriers, or by what other name they may have been styled, were not capable of preventing the oil rising above them in going up or down hill.

Furthermore, due to the inclination of the bottom of the pan or other provision for the protection of the oil, and the direction in which the air currents sweep over it, the oil which is thrown from the bearings into the pan tends to bank on the off side from the direction of rotation, but by reason of the location of the drain opening 15°, the oil will drain rapidly from the pan so that very little, if any, can be picked up by the air and carried to the upper walls of the crank-case or to the cylinders.

Neither the provision of this pan, nor the provision of the baffle 19 can interfere with the flow of oil downward along the side walls 30 of the crank-case, since both the parts referred to are spaced from the walls of the crank-case. On the other hand, the baffle 19 permits this downward flow of oil, as well as prevents the oil being blown up along the 35 wall into the cylinders. Any oil that may be carried upwardly by the air currents, along the inner side of the baffle on reaching the top edge flows down the rear side of the baffle into the sump.

Having described my invention, I claim:

1. In combination with an internal combustion engine having a rotating crank-shaft and a crank-case, of a shield in the form of a pan between the crank-shaft and the bottom of the crank-case, said pan being closed on all four sides and extending along but spaced from the walls of the crank-case, and said pan having at substantially the

lowest part thereof one or more drain openings so that any oil caught in the pan will 50 drain therefrom.

2. In combination with an internal combustion engine having a rotating crank-shaft and a crank-case, of a shield in the form of a pan between the crank-shaft and the bottom of the crank-case, the bottom of said pan having an outlet opening near the center thereof and located near one side wall at substantially the lowest part of the pan 55 so as not to retain oil.

3. In combination with an internal combustion engine having a rotating crank-shaft and a crank-case, of a shield in the form of a pan between the crank-shaft and the bottom of the crank-case, said pan being closed 60 on all four sides, and having a bottom wall inclined downward on the off side from the direction of rotation from substantially one side of the pan to the other.

4. In combination with an internal combustion engine having a rotating crank-shaft and a crank-case, of a pan between the crank-shaft and the bottom of the crank-case, said pan being closed on all four sides 70 and having a bottom which is inclined downwardly on the off side from the direction of rotation and is provided with a drain opening near the center of the pan, lengthwise considered, and adjacent the lower part of the bottom.

5. In an internal combustion engine having a rotating crank-shaft and a crank-case, of a shield in the form of a pan between the crank-shaft and the bottom of the crank-case, and having upstanding side and end 80 walls spaced from the walls of the crank-case, said pan having one or more openings in substantially the lowest part thereof so that any oil caught in the pan will freely drain therefrom, and a baffle secured to the 85 upper part of the crank-case and extending along one wall of the crank-case downwardly below the top of the pan.

In testimony whereof, I hereunto affix my signature.

WILLIAM R. STRICKLAND.
